THERMOSTAT CIRCUIT

Robert J. Parsons, Schenectady, and Ernest J. Heyman, Hampton Manor, N. Y., assignors to Consolidated Car-Heating Company, Inc., Albany, N. Y., a corporation of New York

Application October 31, 1931, Serial No. 572,360

9 Claims. (Cl. 175—375)

For a detailed description of the present form of our invention, reference may be had to the following specification and to the accompanying drawing forming a part thereof.

- 5 Our invention relates to means for enabling a thermostat to control an electric heater, it being understood that the thermostat action may be weak and delicate, while the effects of its action should be strong and forcible. We therefore provide means whereby the thermostat will merely close an electric circuit containing an electromagnet which can perform the work required, such, for instance, as the closure of an electric-heater switch.
- 10 15 In the accompanying drawing, Figs. 1, 2, 3 and 4 show respectively four different forms of our fundamental device.

Referring to Fig. 1, A represents a thermostat, herein indicated as of the bimetallic type. The contact arms a^1 and a^2 are both made of bimetallic strip and are sufficiently flexible to move independently with respect to each other and with respect to the connecting cross piece x. These contacts engage respectively with two fixed contacts b^1 and b^2 . It will be understood that any other form of thermostatic device may be employed to close one set of contacts on a rising temperature and to close a second set on the falling temperature. In Figs. 1, 2 and 3 the high temperature contact b^2 is closed by a rising temperature and is shown engaged by contact a^2 , while a falling temperature will cause the low temperature contact a^1 to close on b^1 . A magnet C has its armature connected to thermostat arm a^1 and, when energized, acts to hold a^1 against its stationary contact b^1 . As a^1 contacts with b^1 there remains a momentary simultaneous contact of a^2 with b^2 , with the result that the current passes from b^1 to a^1 , a^2 and b^2 to ground as illustrated in Figure 1, thereby by-passing the magnet C and resulting in the deenergizing of said magnet. In series with magnet C is a relay D, which controls, at contacts d , d^1 , the electric heater R. The contact of a^1 with b^1 momentarily short circuits both C and D through rheostat S, which causes D to drop its armature and open the circuit of R.

Referring to Fig. 2, C represents a holding magnet arranged so that, when it is energized, it will hold contact arm a^1 on contact with contact b^1 , just as in Fig. 1. Fig. 1 shows the thermostat contacts in the high temperature position with a^2 engaging b^2 . In this position the heater control switch is open as the circuit of magnet C is broken at b^1 . As the temperature falls the contact arms a^1 and a^2 will rise; a^2 will break with b^2 and a^1 will make with b^1 , thus establishing a circuit for the heater control switch from trolley, through resistor S, through contacts b^1 and a^1 , through holding magnet coil C, through heater control switch coil D, to ground. On the

contrary, as the temperature rises, contact arms a^1 and a^2 will both tend to move downward. However, a^1 will still be held up to its contact b^1 as the holding coil C is now energized, with the result that the current will be caused to by-pass the magnet C, through b^1 , a^2 , b^2 and conductor e, whereupon said magnet C will be deenergized. Contact arm a^2 , on the contrary, moves downward, not being held by C, and finally makes contact with b^2 . This short circuits coils C and D, the armature of C lets go and a^1 , which is now under tension, drops down to the position shown in Fig. 1 and opens the circuit for coils C and D. Fig. 2 shows a circuit which gives results similar to those of Fig. 1 except that only coil C is short circuited.

Fig. 3 is similar to Fig. 2 except that coil D is located ahead of C in the circuit.

In Fig. 4 the contact arms a^1 and a^2 are shown in the low temperature position being the reverse of Figs. 1, 2 and 3 in that respect. Heater control switch coil D is now energized from trolley through resistor S, through coil D to ground. When the temperature rises both contact arms a^1 and a^2 move upward, a^2 will break with b^2 and a^1 will make with b^1 . When a^1 makes contact with b^1 it places its holding coil C in parallel with the heater switch coil D, thus reducing the current through it to such a point that it drops out and opens the heater circuit. The temperature will then fall and the contact arms a^1 and a^2 will tend to flex downward, a^2 moving toward the contact b^2 . However, a^1 will be held in contact with b^1 by the holding coil C. As soon as a^2 makes with b^2 , C will be short circuited and a^1 , which is now under tension, will break away from b^1 .

Heretofore devices of this character were not adapted for use where vibration existed, such as on railway cars. By employing a holding coil, with means for energizing and deenergizing it with slight temperature change, we not only provide means of preventing the contacts from being jarred open but also do not impair its sensitivity. Some devices employ a holding coil, or permanent magnet, to hold the contacts from vibrating, but as the magnets are commonly used, the operating range, that is, the temperature change required to operate the contacts, is too great for satisfactory results. As, for example, if the magnet is holding a contact arm, there must be sufficient temperature change to produce enough tension in the thermostat to overcome the pull of the holding magnet; whereas, with our device, the holding coil is energized and deenergized by a thermostat free to move as the temperature changes.

What we claim as new and desire to secure by Letters Patent is:

1. A thermostatic controller comprising means providing a circuit, a holding magnet, a thermo-

stat consisting of two approximately parallel relatively movable temperature responsive portions electrically connected at one end, one of said members being so positioned that it moves into 5 and out of the magnetic field of said magnet in response to a predetermined temperature change, means associated with the other portion of said thermostat for by-passing the holding magnet so as to effect release of the thermostat, and a contact-operating magnet controlled by said thermostat.

2. A thermostatic controller comprising means providing a circuit, a holding magnet, a contact-operating magnet, said magnets being in series 15 in said circuit, an electro-conductive thermostat consisting of two connected electro-conductive members arranged in series in said circuit, one of said members being provided with an electromagnetic portion so positioned that it will automatically move into the magnetic field of the holding magnet as the thermostat responds to a predetermined temperature change, said thermostat being constructed and arranged to control said contact-operating magnet, and means 25 associated with said thermostat for by-passing the holding magnet so as to effect release of said thermostat from magnetic attraction by said magnet.

3. A thermostatic controller comprising means 30 providing a circuit, a holding magnet, a thermostat controlling said circuit, said thermostat consisting of a pair of electrically connected relatively movable temperature responsive portions, one of which is provided with an armature so positioned 35 that it will move into and out of the magnetic field of said holding magnet, a contact-operating magnet controlled by said thermostat, and means associated with the other portion of said thermostat for by-passing the holding magnet so as to deenergize the same.

4. A thermostatic controller comprising means providing a circuit having two relatively spaced contacts, a holding magnet in said circuit, a thermostat consisting of two relatively movable electrically connected temperature responsive portions, one of which is complementary to one of said contacts and the other complementary to the other contact, the first mentioned movable portion being constructed and arranged to be responsive to 45 magnetic attraction and so positioned that it will automatically move into the magnetic field of said magnet as the thermostat responds to a predetermined temperature change, means connected with the second contact to by-pass said holding magnet so as to deenergize the same, and a contact-operating magnet controlled by said thermostat.

5. A thermostatic controller comprising means 60 providing a circuit having a pair of separated contacts, a holding magnet, a thermostat consisting of a pair of relatively movable electrically connected temperature responsive portions, one of which is complementary to one of said contacts and the other complementary to the other contact, the first mentioned thermostat portion having means constructed and arranged to act as an armature for said magnet and so positioned that it will move into and out of the magnetic field of said magnet in response to a predetermined temperature change, a contact-operating magnet controlled by said thermostat, and in series with the first mentioned magnet, and by-pass means connected to the second con-

tact and with said circuit at a position between said magnets.

6. A thermostatic controller comprising means providing a circuit, a holding magnet, a U-shaped thermostat including two relatively movable temperature responsive portions electrically connected at one end, one of which is provided with an armature so positioned that it will automatically move into the magnetic field of said magnet as the thermostat responds to a predetermined temperature change, said portion being complementary to one of said contacts and the other portion of the thermostat being complementary to the other contact, a contact-operating magnet controlled by said thermostat and in series with the first magnet, and by-pass means connecting the second contact with the circuit between the magnets in a manner to by-pass and deenergize said holding magnet.

7. A thermostatic controller comprising means 20 providing a circuit having a pair of spaced apart contacts, a holding magnet, a thermostat consisting of a pair of relatively movable electrically connected temperature responsive portions, one of which is complementary to one of said contacts and in series with said magnet, said last mentioned portion being constructed and arranged to be attracted by said magnet and to automatically move into the magnetic field as the thermostat responds to a predetermined temperature change, the other portion of said thermostat being complementary to the other contact so as to by-pass said magnet, a contact-operating magnet controlled by said thermostat, said thermostat and said contacts being so constructed and arranged as to deenergize said magnet under predetermined temperature conditions.

8. A thermostatic controller comprising means providing a circuit having a pair of spaced apart contacts, a holding magnet, a thermostat consisting of two relatively movable electrically connected temperature responsive portions, one of which is complementary to one of said contacts and in series with said magnet, said last mentioned portion being provided with an armature 40 portion constructed and arranged to be attracted by said magnet and to automatically move into the magnetic field as the thermostat responds to a predetermined temperature change, the other portion of said thermostat being complementary 45 to the other contact so as to by-pass said magnet, a contact-operating magnet controlled by said thermostat, said thermostat and said contacts being so constructed and arranged as to deenergize said magnet under predetermined 50 temperature conditions.

9. A thermostatic controller comprising means providing a circuit, a holding magnet, a thermostat consisting of two approximately parallel electro-conductive members connected at one 60 end and arranged in series with said magnet in said circuit, one of said members having an armature so positioned that it will automatically move into the magnetic field of the magnet as the thermostat responds to a predetermined temperature change, a contact-operating magnet controlled by said thermostat, and circuit means associated with the thermostat for by-passing the holding magnet so as to effect release of said 65 armature.
